HEATED PRESSURE SEAMING DEVICE FOR
PLASTICS

Alvadore M. Andrews, Portland, Oreg.

Application June 7, 1948, Serial No. 31,454

2 Claims. (Cl. 154—42)

1

This invention relates to improvements in construction of the apparatus for joining a plurality of sheets of flexible material, by introducing a thread-like carrier between the sheets to be joined, the said carrier having been drawn through a reservoir of the cement used and given a correct burden of cement for the joinder to be made under heat and pressure.

It is similar to but improved over the parent application infra; the heat and the prolonged pressure being operational differences over the machine shown and claimed in my co-pending application Ser. No. 747,960, filed May 14, 1947, for Apparatus and Method of Joining Pieces of Plastic, now Patent No. 2,500,053, of which this application is a continuation in part.

The objects of the invention are to increase speed of production by increasing the period of forcible contact under pressure to get as good adhesion as that which can be had by the machine of the earlier application and at a much greater speed.

Since the solvents suitable for use in the method and apparatus are of highly volatile character and must be protected from atmosphere contact by passing the saturated thread through a tube right up to the point of inserting said thread between parts to be seamed by cementation, the additional speed makes it possible to use a smaller thread where the same is of fibrous absorbent material or a smaller thread when the thread is a filament of plastic material responsive to the same solvent that seams the pieces of plastic sheet together, as the speed lessens the time during which the solvents can attack the plastic filament and reduce its tensile strength below that requisite to get it and its burden of solvent into place between the sheets to be joined or seamed. The two expressions joined or seamed, are used herein indiscriminately.

A drawing accompanies and forms a part of this specification in which—

Fig. 1 is a side view, partially in section, of the seaming devices in preferred juxtaposition and operable relationship, to be explained;

Fig. 2 is an elevation of the structure of Fig. 1 taken on the plane 2—2, Fig. 1;

Fig. 3 is an enlarged view of the section of Fig. 1 taken on the plane 3—3, Fig. 1;

Fig. 4 is a fragmentary view of the pressure roller, showing the application of a heating element, to be explained;

Fig. 5 is a side view of the upper pressure element or "roller," taken at reduced scale on the 55

plane 5—5, Fig. 3, and broken away to show a side view of the heating element; and

Fig. 6 is a partially sectioned view of the lower pressure wheel that cooperates with the heated upper roller previously referred to, the view being taken on the plane 6—6, Fig. 3, at reduced scale.

Describing the figures and the details thereof with greater particularity. A pressure roller 1 and a pressure wheel 2 are driven at synchronous speed by bevel gear sets 3 and 4 by the vertical shaft 5 and the lay-shaft 6, respectively. The pressure roller is supported by a presser foot 7, movably carried by a head 8, and the pressure wheel 2 is revolubly mounted on a base-plate 10; both the head 8 and the base-plate 10 being a part of the machine structure, the broken away parts of which are not shown but which may be ascertained, if desirable, from the parent application, the relationship being unmistakable.

20 A tube 11, contains a thread 12, which may either be fibrous absorbent material such as cotton or may be a filament of plastic, usually identical with that of the sheets to be joined, such as flexible vinylite plastic. The thread 12 is supplied from a ball or spool and the end first passed through a reservoir containing solvent that responsively attacks the plastic sheets to be joined and the filament of plastic if one is used for the thread 12. In case a fibrous thread is used for 12, dependence will be upon its soaking up a small quantity of the solvent, which is rapidly pulled through the tube 11 by feeding the thread between sheets of plastic such as 13 and 14 which are concurrently drawn between the pressure roller 1 and the pressure wheel 2, by operation of said roller and said wheel by operation of the bevel gear sets 3 and 4; power being applied through the vertical shaft 5, and the lay-shaft 6, from a source not shown.

When the thread 12 is thus drawn in between the sheets of plastic 13 and 14, pressure applied by the roller 1 and the wheel 2, expresses solvent absorbed by the fabric thread 12 or carried in a partially dissolved outer surface, if 12 is a filament of plastic, and brings all three elements of the seam into firm contact. The roller 1 has a heating means to be described, which greatly assists in the making an adequate seam and the sheets pass, still held in contact, over the idle roller 15, being supported in arcuate contact with the heated roller 1 by the belt 16 for nearly a quadrant of the surface of the roller 1, as shown at 17 in Fig. 1.

The pressure wheel 2, is provided with a belt traction surface supplied by a disc of resilient

rubber 10, with a grooved edge 10 as shown. The belt 16 is of round section and may be made of any suitable material. The wheel 2, is supported by the journal 20. The roller 1, is supported by the journal 21. The perimeter of the roller 1 is preferably made of two angular pieces of annealed glass 22 and 23, having a ground perimeter surface 24, as indicated by exaggerating the roughness required at 24 in Fig. 4.

Heating of the roller 1 is accomplished by a circular electrically heated element 26, laid into a recess 21, formed by two half-round grooves formed in the glass elements 22 and 23. Current for heating is supplied by the circuit 28, with which in series is the variable resistance 29 which, by leads 30 and 31 and the commutator rings 32 and 33, receives current from the circuit 28 by the brushes 34 and 35.

The pressure wheel 2, preferably has a pressure ridge 28 of sufficient height and width to apply pressure of desired amount to the soaked thread 12 through the sheets, expressing its cement between the sheets. The resiliently supported belt 16 bears against the roller 1 tight enough to limit the spread of cementitious material on that side and define a straight seam.

The side parts of the roller 1 are preferably made of a strong synthetic of the Bakelite type and the parts held together by suitable fastenings such as the screws 38 and 39. The outside surfaces of the glass parts 22 and 23, as indicated by legend, are silvered to improve their heat directional properties and send the most of the heat towards the perimeter of the roller 1, of which they form a part.

This construction permits a relatively long application of heat to the two plastic parts to be seamed, while holding them in firm contact, thus satisfying the stated objects of the invention in an excellent manner. The employment of the belt 16, holds the sheets such as 13 and 14 in a firm supporting grip, preventing side slip of the sheets, while their contacting surfaces are slippery with solvent, before the heat has had an opportunity to effect the firm joinder.

Having fully disclosed my invention so that those familiar with the art to which it appertains can make and use it, what I claim as new and desire to secure by Letters Patent, is:

1. A heated pressure seaming device of the solvent carrying thread type wherewith two pieces of plastic are subjected to heat and pressure with a solvent carrying thread between the said pieces, characterized by an upper driven revolvable pressure roller, an electrical heating element embedded therein in substantial concentricity with and of less diameter than the perimeter of the roller, and a pressure wheel supported for power drive immediately beneath said roller, the said roller having a slightly roughened surface and the wheel having a mating raised surface to determine the width of the zone to which pressure is applied.
2. In an apparatus of the class described, the combination comprising a pair of cooperating roller elements mounted for rotation about parallel axes, means biasing the peripheries of said roller elements together, means for driving said roller elements at the same speed, said roller elements being adapt'd to receive therebetween a pair of plastic sheets to be bonded together, the peripheral portion of one of said roller elements being formed of glass and having an electric heating element imbedded therein, the inner surface of said glass portion being provided with a coating of reflective material.
